UNITED STATES PATENT OFFICE.

SAMUEL D. IRWIN, OF FLOYDADA, AND STEPHEN ELBERT JOHNSON, JR., OF SPUR,
TEXAS.

COTTON-BUR SEPARATOR.

1,276,370.

Specification of Letters Patent.

Patented Aug. 20, 1918.

Application filed May 20, 1918. Serial No. 235,535.

To all whom it may concern:

Be it known that we, SAMUEL D. IRWIN and STEPHEN E. JOHNSON, Jr., citizens of the United States, residing, respectively, at 5 Floydada and Spur, in the counties of Floyd and Dickens and State of Texas, have invented certain new and useful Improvements in Cotton-Bur Separators; and we do hereby declare the following to be a 10 full, clear, and exact description of the invention, such as will enable others skilled in the art to which it appertains to make and use the same, reference being had to the accompanying drawings, and to the letters 15 and figures of reference marked thereon, which form a part of this specification.

This invention relates to new and useful improvements in apparatus for separating burs from cotton lint.

20 A frost bitten cotton bur usually opens but a slight distance, but contains a considerable amount of lint, therefore making it necessary to break open the bur and separate the lint from the bur and shale before the gin 25 can successfully handle the product. Cotton in bur is frequently gathered while dew is upon them and hence have no chance to dry out and if attempted to gin in this condition, the moist lint with the addition of 30 vegetable gum upon the bur twines about the cross wire in the screen of the usual gin machinery and cutting off the screen surface causing the same to choke up.

By the provision of the features of the 35 present invention these features are eliminated and a machine is afforded having various details of construction, combinations and arrangements of parts which will be hereinafter fully described, shown in the accompanying drawings and then specifically defined in the appended claims.

40 Our invention is illustrated in the accompanying drawings, which with the letters of reference marked thereon form a part of this specification and in which:

Figure 1 is a vertical sectional view of the apparatus.

45 Fig. 2 is a front elevation thereof, a portion being broken away to better illustrate the parts.

Fig. 3 is a sectional view on line 3—3 of Fig. 2.

50 Fig. 4 is a view in elevation of a series of inclined blades spaced apart, and

Fig. 5 is a sectional view on line 5—5 of Fig. 4 looking in the direction of the arrow.

Reference now being had to the details of the drawings by numerals:

1 designates a casing in the walls of which are mounted the shafts 2, carrying the drums 3 over which the endless conveyer 4 passes having teeth 5 thereon for the purpose of engaging the lint as it comes in contact with the belt. A feed pipe 6 leads into said casing and into which the cotton as it is unloaded is blown into the separator. A series of inclined blades 7 are disposed at an inclination in the casing over the endless conveyer as shown in Fig. 1 of the drawings, and against which the cotton is blown, being 70 deflected downward against the belt.

Other blades 8, arranged at inclinations to one another and spaced apart a slight distance, are mounted within the casing and spaced apart from the conveyer, a suitable 75 space 9 intervening between the outer portions of the blades 8 and the wall 10 of the casing, said space 9 being adapted to receive such foreign matter as broken burs which may pass through the spaces between the 80 blades 8. A conveyer 11 is mounted at the lower end of the casing and is adapted to carry away such foreign matter as may fall to the bottom of the casing. Said endless conveyer 4 is driven by power applied to the 85 pulley 12 fixed to the shaft 2 carrying the lower drum and upon which shaft the pulleys 14 and 15 are mounted. A pulley 11' is fixed to the shaft of the conveyer 11 and has belted connections 13' with a pulley 90 2' upon the shaft 2.

By referring to the detailed views of the drawings, it will be noted that the series of blades 8 are mounted in cleats 16 spaced apart and the inner end of each blade is 95 rounded as at 16'.

A suitable space 17 intervenes between the endless belt 4 and the inner ends of the series of blades 8 and in which the larger portions of the burs which do not pass between the blades 8 and which are thrown against the blades 8 by centrifugal force, are adapted to fall into a screw conveyer 18 having a shaft 18' upon which a driving pulley 19 is fixed, adapted to have belted 100 connection with the pulley 15. A brush 20 is mounted in suitable bearings in the casing and in the trough 21 which communicates

with the interior of the casing 1, said brush being so positioned that it will contact with the endless conveyer 4 and remove the lint from the teeth thereon. Said brush is keyed 5 to a shaft 22 drawn by belted connection with the pulley 14 upon the shaft 2.

The operation of our apparatus is as follows: The cotton is unloaded from the wagon 10 into the pipe 6 and against the blades 7 which are disposed at an inclination to one another across the feed pipe and which blades will obstruct the passage of the current of air, the blades thus causing the cotton and burs to be thrown against the teeth 15 upon the endless conveyer belt. The teeth upon the endless conveyer belt will carry the cotton against the inner ends of the blades 8 and the bur being heavier than the 20 lint will be thrown by centrifugal force against the blades 8 and tend to separate the lint therefrom, portions of the burs passing through the blades 8 and into the space 9. The particles of burs and other foreign 25 matter entering the space 9 will fall by gravity into the conveyer 11 and be conveyed away. Larger particles of burs which do not pass through the blades 8 will fall into the space 17 into the conveyer 18. The 30 lint which adheres to the teeth of the belt will be separated therefrom by the brush 20 and drawn to the gin through the passage way in which the brush is located.

What we claim to be new is:

35 1. A bur separator in combination with a casing having a feed pipe into which cotton is introduced, an endless conveyer belt with teeth thereon, a series of deflector blades positioned over said belt and designed to 40 deflect the cotton and burs toward the belt, a series of transversely disposed blades spaced apart from one another and posi-

tioned intermediate the conveyer belt and the vertical wall of the casing, the inner ends of said series of blades having round 45 edges, conveyers in the lower portions of the casing, and a rotary brush adapted to separate the lint from the belt.

2. A bur separator in combination with a 50 casing having a feed pipe into which cotton is introduced, an endless conveyer belt with teeth thereon, a series of deflector blades positioned over said belt and designed to deflect the cotton and burs toward the belt, a series of transversely disposed inclined 55 blades spaced from one another and extending upon either side of the conveyer belt and spaced therefrom, conveyers at the lower portions of the casing, and a rotary brush 60 for separating the lint from the conveyer.

3. A bur separator in combination with a 65 casing having a feed pipe into which cotton is introduced, an endless conveyer belt with teeth thereon, a series of deflector blades positioned over said belt and designed to deflect the cotton and burs toward the belt, a series of transversely disposed inclined 70 blades spaced from one another and extending upon either side of the conveyer belt, and underneath the same and spaced apart from said conveyer, the conveyers mounted one above the other and adapted to carry 75 away foreign matter which comes in contact with or passes between said series of blades, and a rotary brush mounted in the casing and adapted to separate the lint from the teeth of the belt.

In testimony whereof we hereunto affix our signatures in presence of two witnesses.

SAMUEL D. IRWIN.

STEPHEN ELBERT JOHNSON, JR.
